UNITED STATES PATENT OFFICE.

JOHN R. REPLEGLE, OF DETROIT, MICHIGAN, ASSIGNOR TO ELECTRIC REFRIGERATION CORPORATION, OF DETROIT, MICHIGAN, A CORPORATION OF MICHIGAN.

MECHANICALLY-REFRIGERATED CABINET.

Application filed February 5, 1927. Serial No. 166,051.

This invention relates to mechanically refrigerated cabinets of the type in which different ranges of temperature are maintained in a plurality of food storage compartments.

An object of this invention is to provide a mechanically refrigerated cabinet for the storage of food and the like in which the circulation of a heat absorbing fluid contacting with a cooling unit and food containers in a plurality of compartments is controlled to respectively regulate the temperature maintained in the different compartments.

Another object of this invention is to provide a refrigerated cabinet, of the multiple compartment type having a heat absorbing fluid circulating through the compartments and in contact with a cooling unit, with externally extending manually operated mechanism for controlling the flow of the heat absorbing fluid through the compartments to regulate the temperature maintained therein.

These and other objects of the invention will be more apparent as the description progresses, in which like characters designate like parts in the accompanying drawings illustrating a preferred embodiment of the invention.

In the drawings:

Fig. 1 is a partial vertical elongated section through a cabinet illustrating a shutter valve mechanism for controlling the circulation of a heat absorbing fluid through the cabinet compartments.

Fig. 2 is a vertical transverse sectional view taken substantially on the line 2-2 of Fig. 1 showing the shutter valve mechanism in end elevation.

Figs. 3 and 4 are detail sectional views taken on the lines 3-3 and 4-4 of Fig. 2.

Fig. 5 is a fragmentary perspective view of the shutter valve mechanism for controlling the circulation of the heat absorbing fluid through the cabinet compartments.

The cabinet illustrated in the drawings with which my invention is associated is adapted for storage of ice cream, bottled liquids and the like, and comprises the end walls 10, side walls 11 and the bottom wall 12. These walls are preferably built up of wood panels lined with corkboard insulation and are covered externally with a metal cover to provide the exterior shell of the

cabinet. The inner faces of these walls are lined with metal panels 13 of copper or similar non-corrosive material, thus forming a large internal chamber. Supported within this chamber is an enclosed tank structure 60 14 which is rigidly held in place by the top wall 15 of the cabinet. One or more open top food storage sleeves or receptacles 16 are arranged to extend into the tank 14 and register with openings in the top wall 15, 65 these openings being closed by the covers or lids 17 so that when the lids are removed access may be had to the interior of the food storage receptacles. A heat absorbing fluid, preferably brine, is contained within the 70 tank 14, which is usually termed the brine tank, and surrounds the sleeves 16.

At intermediate points of the tank 14 there are provided partition walls which divide the tank into compartments A, B and 75 C. The partition walls are each comprised of a stationary perforated plate 21, the perforations 22 therein being preferably elongated slots. The outer vertical edges of the stationary plates 21 are turned inwardly, 80 as at 23, to provide a channel 24, and then return bent and flanged laterally as at 25, the flanges 25 being riveted or otherwise secured to the side walls 14^a of the tank 14. Guided within the grooves or channels 24 at 85 both sides of the plates 21 are movable perforated plates 25^a, the perforations 26 in the plates 25^a being arranged to register with the perforations 22 in one position to permit the heat absorbing fluid or brine to 90 circulate through the partition walls. Figs. 1 and 2 show these perforations in registration, while Figs. 4 and 5 show the perforations out of registration and in a position to 95 shut off communication between the food containing compartments and the evaporator compartment A.

The movable plates 25^a are arranged to be manually operated from a point externally of the cabinet. Secured to the upper 100 edge of each of the plates 25^a is an extension 27 provided with external threads on the upper end. A nut 28 is screwed on to the threaded portion of each of the extensions 27 and as these nuts are screwed down 105 the plates 25 are lifted, and as the nuts are backed up on the threads the plates 25 are permitted to fall by gravity. The relation between the plates 21 and 25^a is such that as the plates 25^a reach their lowermost posi-

- tion the perforations in the associated plates are in full registration with each other, and as the plates 25^a are raised the openings through the walls 20 are made smaller.
- 5 With this construction it will be seen how the size of the openings through the wall 20 can be varied as desired to control the quantity of brine flowing therethrough.
- An evaporator D, provided with the de-
- 10 pending pipe loops 28, is rigidly supported within the compartment A, and is in circuit with a conventional type of mechanical refrigeration mechanism (not shown), the evaporator being supported by means of the
- 15 upper bracket 29 and the lower bracket 30. In the operation of a mechanically refrigerated cabinet the evaporator, or cooling unit, absorbs heat from the brine, or other suitable heat absorbing fluid contained with-
- 20 in the compartment A, and when the perforations in the plates 21 and 25^a are in registration with each other the cooled brine is permitted to freely circulate in the brine tank. This circulation of the brine is con-
- 25 trolled by the manually operated mechanism above described, which varies the size of the openings through the partition wall 20 to control the flow of the brine. As the openings are made smaller in the partition walls, the flow of the brine is restricted and the heat units in compartments B and C are partially held back, the evaporator in this case absorbing a lesser amount of heat units from compartments B and C. The purpose of this control mechanism is to regulate the temperature within the compartments B and C by controlling the circulation of the brine; the greater the circulation the colder the compartment, and the temperature of
- 30 either food compartment rises in direct proportion as the circulation is progressively shut off by varying the size of the openings in the partition walls. From the above description of the mechanism and its operation
- 35 it will be seen how the temperatures in the compartments B and C can be regulated as desired.

The temperature in compartment A re-
50 mains practically constant, this temperature being controlled, however, by mechanism set to produce the desired result, whereas the temperature in compartment B and C can be varied at will, it being regulated by the shutter type of control mechanism above de-
scribed. The design of the cabinet is such that the temperature in compartment A is maintained lower than the temperature in compartments B and C which can be varied as required for different kinds of food stored therein.

Various changes can be made in the mech-
anism for controlling the circulation of the
brine in the tank without departing from
the spirit of my invention and the scope of
what I claim.

What I claim is:

1. In a mechanically refrigerated cabinet, a closed tank containing a heat absorbing fluid and provided with heat conducting partition dividing the tank into a plurality 70 of compartments, said partition provided with perforations therethrough for permitting the heat absorbing fluid to circulate from one compartment to the other, one or more separate food storage receptacles extending into one of said compartments and the fluid therein, a mechanically refrigerated heat transfer element extending into another of said compartments and the fluid therein, and means for controlling the quantity of 80 fluid permitted to flow through the perforations in said partition from one compartment to the other to regulate the temperature within the compartment containing said food storage receptacles. 85
2. In a mechanically refrigerated cabinet, a closed tank containing a heat absorbing fluid and provided with a partition dividing the tank into a plurality of compartments, said partition comprising two perforated 90 plates, one being adjustable with respect to the other, one or more food storage receptacles extending into one of said compartments and the fluid therein, a mechanically refrigerated heat transfer element extending 95 into another of said compartments and the fluid therein, and means manually operable from the exterior of the cabinet for adjusting said adjustable perforated plate for controlling the quantity of fluid permitted to 100 flow through said perforations from one compartment to the other to regulate the temperature in the compartment containing said food storage receptacles.

3. In a mechanically refrigerated cabinet, 105 a closed tank containing a heat absorbing fluid, partitions dividing said tank into a plurality of adjacent compartments, said partitions being formed to permit circula-
tion of the fluid therethrough and including 110 a movable portion for regulating the flow of the heat absorbing fluid therethrough, and a mechanically refrigerated heat transfer element extending into one of the compartments.

4. In a mechanically refrigerated cabinet, 115 a closed tank adapted to receive a heat absorbing fluid, partitions formed of a plurality of apertured plates dividing said tank into a plurality of adjacent compartments, one of the plates of each partition being movable to regulate the flow of the heat absorbing fluid between adjacent compartments, and a mechanically refrigerated heat transfer element extending into one of the compartments.

5. In a mechanically refrigerated cabinet, a closed tank adapted to receive a heat absorbing fluid, metallic partitions formed of a plurality of adjacent plates for dividing

said tank into a plurality of adjoining compartments, one of the plates of each partition being movable in a vertical direction for controlling the circulation of the heat absorbing fluid between adjacent compartments, and a mechanically refrigerated heat transfer element extending into one of the compartments.

6. In a mechanically refrigerated cabinet, 10 a closed tank containing a heat absorbing fluid, perforated heat conducting partitions in said tank forming compartments, a mechanically refrigerated heat transfer element extending into one of the compartments, and adjustable means for regulating 15 the flow of the heat absorbing fluid from said compartment containing the heat transfer element to the other compartments, the regulation of said means permitting regulation 20 of the temperature of the compartments adjacent said heat transfer element.

7. In a mechanically refrigerated cabinet, a closed tank adapted to receive a heat absorbing fluid, metallic plates forming parti-

tions dividing said tank into a plurality of adjacent compartments, said plates having apertures therethrough, one of said plates being movable for controlling the circulation of the heat absorbing fluid through the compartments by alignment of the apertures, and a mechanically refrigerated heat transfer element extending into one of the compartments.

8. In a mechanically refrigerated cabinet, 35 a closed tank adapted to receive a heat absorbing fluid, metallic plates forming partitions dividing said tank into a plurality of transversely-arranged compartments, said plates having apertures therethrough, one of said plates being movable for controlling the 40 circulation of the heat absorbing fluid through the aperture in said partitions, and a mechanically refrigerated heat transfer element extending into the central compartment.

In testimony whereof, I hereunto affix my signature.

JOHN R. REPLOGLE.
